UNITED STATES PATENT OFFICE.

HARRY A. TAYLOR, OF NEW YORK, N. Y.

GLOVE.

1,162,821.

Specification of Letters Patent.

Patented Dec. 7, 1915.

Application filed December 9, 1914. Serial No. 876,375.

To all whom it may concern:

Be it known that I, HARRY A. TAYLOR, a citizen of the United States, and a resident of the borough of Manhattan, city, county, and State of New York, have invented certain new and useful Improvements in Gloves, of which the following is a specification, reference being had to the accompanying drawings.

10 The invention relates to a new method of producing the so-called "points" or "sticks," (hereinafter called points) upon the outer surface of the back of the glove and it consists in so forming the points that 15 the gathering, or as it is sometimes called, pinching of the material composing the gloves, which occasions distortion and inelasticity therein, is avoided and also superior finish and additional ornamentation 20 supplied. The construction may be carried into effect in a variety of ways, all modifications of the fundamental idea, some of which will be illustrated and described below.

25 The invention is applicable to gloves and mittens of practically all forms and made of practically all materials. I have found it most desirable in conjunction with the finer grades of gloves, such as those made from fine fabrics or leather.

30 Referring to the drawings, Figure 1 shows a plan view of the back of a glove provided with points which embody the invention; Fig. 2 shows a longitudinal sectional view taken on the line 2—2 of Fig. 1 and looking 35 in the direction of the arrow; Fig. 3 shows a plan view of a part of the back of a glove illustrating a single point embodying a modified construction; Fig. 4 shows a longitudinal sectional view on the line 4—4 of

40 Fig. 3 and looking in the direction of the arrow; Fig. 5 shows a transverse sectional view taken on the line 5—5 of Fig. 3 and looking in the direction of the arrow; Fig. 6 shows a view similar to Fig. 3, but illustrating a modified construction; Fig. 7 shows a plan view of that which is shown in Fig. 6, showing the reverse or inside of the glove back; Fig. 8 shows a longitudinal sectional view on the line 8—8 of Fig. 7 and looking 45 in the direction of the arrow; Fig. 9 shows a transverse sectional view on the line 9—9 of Fig. 6 and looking in the direction of the arrow; Fig. 10 shows a transverse sectional view of a modified construction substantially 50 the same as Figs. 6 and 9, but so constructed as to show a plurality of separate and de-

fined ribs in a point similar to that shown in Fig. 3.

The ornamentation of the backs of gloves by means of points is very old and they have 50 heretofore been made in a variety of ways, principally by gathering together, or, as it is called, pinching the material of which the glove is made and sewing the pinched or gathered part together so as to constitute one 55 or more ribs in it, each of which gatherings constitutes one of the points. Sometimes to give greater projection or relief to the point a cord of greater or less size has been enclosed within each gathered or pinched part 60 of the glove material and held in place by suitable stitching. This method is objectionable for a number of reasons, more especially that the gathering or pinching of the material and the necessary stitching to hold 65 the gathers or ribs in place materially reduce the elasticity of the back of the glove and also at the end of the gathered or pinched parts there is formed an unsightly 70 and distorted portion where the rib ceases 75 and the material flattens out into the general plane of the back of the glove; also the strain applied to the stitches, if the fit of the glove be at all snug, is apt to break out fine fabrics such as high grade silk gloves, and 80 also to pull apart to a certain extent, exposing the stitches and presenting an unfinished appearance. Also in certain qualities of glove material the gathering or pinching 85 of the glove back, particularly if a cord be 90 employed within the gathered part, results in a straining of the glove material so as to destroy or injure its surface texture in such manner that it quickly roughens up and becomes unsightly. 95

Under my invention I obviate all the difficulties above suggested and produce a handsomer and more durable glove than any known to me. The points may be made in a variety of ways, all embodying the same 100 fundamental idea, that is to say, a separate piece of durable and decorative fabric, silk, fine leather or the like, is cut of the proper size and shape and is stitched or otherwise secured upon the back of the glove when it 105 is smoothed out flat and the edges of the added piece are securely attached to the glove material, preferably by decorative stitching. Sometimes to produce greater projection, cord or other material may be 110 applied either upon the outside or inside of the glove and then covered with the fin-

ishing material, as hereinafter explained. Further decoration may be secured by ornamental stitching and various attractive effects secured by the use of cords, etc., all 5 as hereinafter set forth.

In the drawings I show in Figs. 1 and 2 the simplest form of the invention. In them 1 represents the glove back, 2, 2, the strips of finishing material cut of the proper 10 size and shape to constitute the point and 3 decorative stitching which I prefer shall be so-called chain stitching, whereby all of the edges of the strips 2 are secured to the back of the glove. The strips may be of such material as preferred, the same or different 15 from that constituting the glove itself and the color of the strips and of the stitching may be such as preferred. In this way contrasting color effects and peculiarly attractive combinations may be produced.

In Figs. 3, 4 and 5 I show a form of the invention in which the points are given greater projection than that shown in Figs. 1 and 2 which do not present much relief. 25 In these figures, like reference numerals indicate like parts, but beneath the strips of material 2 and on the outside of the glove are placed three cords 4, the ends 5 of which (see Fig. 4) are passed through holes or 30 openings made in the glove material to the inside thereof, and in order to give to the finishing material in each point the appearance of separated ribs, lines of stitching 6 passed through the strips of material and 35 the glove material between each cord.

In Figs. 6, 7, 8 and 9, I show still another modified construction. In them also like reference numerals indicate like parts except that in this instance the cords are placed 40 upon the inside of the glove material and it is gathered slightly by cross stitching 7 (see Figs. 7, 8 and 9) so as to hold the cords 4, in position.

In Fig. 10 I show a construction in which 45 the parts are indicated by the same reference numerals as before but in this instance three cords 4 are on the inside of the glove material, and in order to give the appearance of parallel ribs, I draw down the finishing material 2 by stitches 8, performing 50 substantially the same office as the stitches 6 in Fig. 5.

As above suggested, the material forming the finishing strips may be stich as preferred. Leather or fabric will ordinarily be 55

found the best and it may be the same as that constituting the body of the glove or different, as preferred. It may also be transparent, or sufficiently so to give the points the color effect of the underlying material. Also the color of the strips and of the stitching and the special character of the stitching, that surrounding the finishing strips and that employed to draw the finishing material into separated ribs, may be 60 such as preferred; thus an almost indefinite variety of color effects and attractive appearance may be produced.

It will be obvious to those who are familiar with such matters that the above described constructions are examples only of various forms in which the invention may be practised and that others may be employed and yet the essentials of the invention be retained.

I claim:

1. A glove having a point consisting of one or more cords attached to the back of the glove so as to secure projection or relief thereof, a strip of finishing material of the desired size and shape superimposed thereon and secured to the outside of the glove about all its edges.

2. A glove having a point consisting of one or more cords secured to the back of the glove by transverse stitching, a strip of finishing material of the desired size and shape superimposed upon the back of the glove in registry with said cords and secured to the glove throughout all its edges and stitching 90 passing through said strip and the glove material between the cords, thus drawing down the strip to produce the effect of ribs.

3. A glove having a point consisting of one or more cords secured to the inside of the back of the glove by transverse stitching which partially gathers the glove material and gives the desired projection or relief to the point, a strip of material of the desired size and shape superimposed upon the back 100 of the glove in registry with the cords and secured to the glove material by stitching.

In testimony whereof I have signed my name to this specification in the presence of two subscribing witnesses.

HARRY A. TAYLOR.
